UNITED STATES PATENT OFFICE.

EDWARD S. DE TAMBLE, OF SAN FRANCISCO, CALIFORNIA.

DESIGN FOR AN AUTO-HEADLIGHT LENS.

53,489.

Specification for Design.

Patented July 8, 1919.

Application filed March 13, 1919. Serial No. 282,516. Term of patent 14 years.

To all whom it may concern:

Be it known that I, EDWARD S. DE TAMBLE, a citizen of the United States, residing in the city and county of San Francisco and State of California, have invented a new, original, and ornamental Design for Auto-Headlight Lenses, of which the following is a specification, reference being

had to the accompanying drawing, forming part thereof.

The figure is a front elevation of an auto headlight lens, showing my new design.

I claim:

The ornamental design for an auto headlight lens, as shown.

EDWARD S. DE TAMBLE.
